DESIGN FOR A SPECTACLE FRAME

Altina Sanders, New York, N. Y.

Application December 6, 1938, Serial No. 81,597

Term of patent 7 years

To all whom it may concern:

Be it known that I, Altina Sanders, a citizen of the United States and resident of New York, in the city, county and State of New York, have invented a new, original, and ornamental Design for a Spectacle Frame, of which the following is a specification, reference being had to the accompanying drawing, forming part thereof.

In the drawing:

Fig. 1 is a front view of a spectacle frame showing my new design, the temples being shown in folded position.

Fig. 2 is a top plan view thereof, the temples being in an open or normal wearing position.

Fig. 3 is a side view of the spectacle frame shown in Fig. 2.

I claim:

The ornamental design for a spectacle frame, substantially as shown and described.

ALTINA SANDERS.
